GAS BURNER CONTROL

Walter S. McDonough, Philadelphia, Pa.

Application August 23, 1937, Serial No. 160,401

2 Claims. (Cl. 251—163)

This invention has to do with the gas burner valves and is concerned primarily with means for mechanically controlling operation of a valve.

While a gas burner, such as is used for home cooking purposes, is turned on in varying degrees during the normal use of the same, the degree of heat which is used more than any other is the so-called simmering point, that is the amount of gas that is supplied to the burner will be just sufficient to support combustion. Heretofore there have been proposed certain devices for mechanically indicating when the gas burner is turned to this simmering point, such device being illustrated and described in the co-pending application of Walter S. McDonough, Serial No. 137,187, filed April 16, 1937, entitled "Gas burner control".

The present invention has in view as its foremost objective the provision of control mechanism for a gas burner of the same general type set forth in the above-identified co-pending application, but which device is improved to afford distinct advantages over known devices of this character.

The invention has in view as a further objective the provision of control mechanism of the character above indicated which is readily assembled on the conventional gas burner stove and which is susceptible of being adjusted to vary the simmering point which is determined by the mechanism.

These and other more detailed objects and advantages will in part become apparent and in part be hereinafter stated as the description of the invention proceeds.

The invention, therefore, comprises novel and improved control mechanism which is readily and easily assembled on the conventional gas burner and which is adjustable to vary the simmering point, which is determined by the mechanism.

For a full and more complete understanding of the invention reference may be had to the following description and accompanying drawing, wherein

Figure 1 is a side view, partly in section and partly in elevation, of a gas burner with the control mechanism of this invention applied thereto,

Figure 2 is an elevational showing taken at right angles to the showing of Figure 1 and develops the operating member for the gas burner together with the operating member for adjusting the simmering point,

Figure 3 is a detailed view in perspective of the supporting yoke constituting a part of the control mechanism,

Figure 4 is another perspective illustration of one of the ring elements of the mechanism,

Figure 5 is an end view, partly in section and partly in elevation, of the ring member shown in Figure 4 with the adjusting lever applied thereto,

Figure 6 is a perspective view of the lever and associated structure per se, and

Figure 7 is a perspective view of the inner member of the mechanism.

Referring now to the drawing wherein like reference characters denote corresponding parts, the wall of a stove which may be of any conventional design is shown fragmentarily in Figure 1 and designated 10. This wall 10 is formed with an opening 11 through which extends a shaft 12 that constitutes the gas burner control. This shaft 12 extends into the interior of the stove where it is operatively connected to the valve that controls the flow of gas to the particular burner, the valve mechanism being referred to generally at V. This valve mechanism V may be supported from supporting structure which constitutes a part of the stove and which is identified at 13.

The shaft 12 projects through the opening 11 on the front face of the stove and mounted thereon in a well-known manner, as by a set screw 14, is an operating member 15. Ordinarily this operating member 15 carries a circular shield 16 formed as an integral part thereof, and which shield conceals the opening 11. The wall 10 of the stove is formed with an arcuate slot at 17 for a purpose to be hereinafter described, and it is notable that this slot is disposed beyond the peripheral edge of the shield 16.

The control mechanism of this invention is carried by a yoke member that is shown in Figure 3 and which is referred to in its entirety by the reference character Y. The yoke Y comprises a circularly shaped disc member 18, formed with an opening 19, through which passes the shaft 12. When the yoke Y is assembled on the shaft 12, the outer face of the disk 18 is disposed in engagement with the inner face of the wall 10. Extending from diametrically opposite points, and preferably integrally therewith, are a pair of tabs 20 and 21, each of which is formed with ears 22 and 23. The ears 23 are formed with openings 24, and threaded bolts 25 pass through openings in the supporting structure 13 and the openings 24 to secure the yoke Y in position. When the yoke Y is in position, the space between the disk 18 and ears 22 and 23 houses the control mechanism.

Ordinarily the valves of gas burners of the

type with which this invention is concerned include a spring for maintaining a valve element seated, and this spring is shown in Figure 1 at 26 and is illustrated as being positioned about 5 the shaft 12. This spring 26 is availed of to perform certain functions in the present control mechanism as will be hereinafter pointed out.

The inner face of the disk 18 is lined with a 10 friction material such as the gasket illustrated at 27, the gasket having an opening to accommodate the shaft 12.

The ring member shown in Figure 7 is designated 28 and is shown as formed with a groove 29 on its outer periphery, and this groove 29 is 15 adapted to receive a ball detent, as will be later described, to establish a stop. The ring member 28 is formed with a bore 30 for receiving the shaft 12 and a recess extends from the outer periphery to the bore 30, and which recess is designated 31. The recess 31 is cylindrical in shape 20 and is threaded to receive a set screw 32. This set screw 32 is pointed in a well-known manner and is adapted to engage the shaft 12 to securely anchor the ring member 28 in position thereon.

An outer ring member is designated 33 and is 25 shown in detail in Figure 4. The ring member 33 has an inner cylindrical wall 34 that defines a recess which receives the inner ring member 28. This ring member 33 also has an outer cylindrical wall 35 which is formed with a radial extending recess 36 that constitutes a housing for a spring actuated ball detent 37, the spring for the detent 37 being shown at 38. On each side of the recess 36, the outer cylindrical surface 35 is 30 formed with a pair of threaded openings 39. A spring retaining plate 40 has an arcuate curvature corresponding to the cylindrical wall 35 and is formed with spaced openings 41. Screws 42 are threaded through the openings 41 into the openings 39 and thus maintain the retaining plate 40 in position over the recess 36.

As is clearly brought out in Figure 6, the retaining plate 40 is formed with an offset extension 43 that projects through the arcuate slot 45 17 and is thus constituted a thumb lever for adjusting the position of the ring member 33.

One flat face of the ring member 33 is roughened or corrugated as shown at 44 in Figure 3, and this roughened surface engages the 50 friction material 27.

The opposite flat face of the ring member 33 is formed with a plurality of openings 45, which are availed of as a means for anchoring a cover plate designated 46 to the ring member 33, screws shown at 47 being availed of as the anchoring medium. As shown in Figure 1, the cover plate 46 extends over the inner ring member 28, and engaging the outer surface of this cover plate 46 is the spring 26. Thus, because of 55 the presence of the spring 26, a certain required amount of pressure is maintained on the ring 33 to urge the roughened surface 44 against the friction material 27 whereby the ring 33 is yieldably maintained in position. However, the resistance offered by the engagement of the roughened surface 44 and friction material 27 may be overcome by a person availing of the thumb lever 43, and the ring member 33, thus adjusted.

The ring member 28 is so positioned on the shaft 12 that upon the valve V being opened sufficiently to supply the required amount of gas for the desired simmering point, the ball detent 37 will be received in the groove 29. Obviously, by applying a necessary amount of rota-

tive force to the operating member 15, the resistance to the rotative movement offered by the ball detent 37 and groove 29 may be overcome, and the valve V be completely closed, or when the force is applied in the opposite direction, 5 opened further.

However, one operating the member 15 can readily ascertain when the ball detent 37 is received in the groove 29, either because of the click that will be heard, or also because of the 10 resistance necessary to be overcome in order to rotate the shaft 12 and move the ball detent 37 out of the groove 29.

In assembling or disassembling the control mechanism, above described, on the shaft 12, it is 15 notable that by aligning the recesses 31 in the inner ring member and 36 in the outer ring member a suitable tool may be inserted into the aligned recesses for threading home or unscrewing the said screw 32.

Each of the rings 28 and 33 may be made from any suitable material, but the invention has in view as a preferred material a non-corrosive metal such as bronze.

While a preferred specific embodiment of the 25 invention is hereinbefore set forth it is to be clearly understood that I am not to be limited to the exact construction illustrated and described, because various modifications of these 30 details may be provided in putting the invention into practice within the purview of the appended claims.

I claim:

1. Control mechanism for a valve operating shaft which extends through an opening in a 35 plate comprising a yoke having a front disc in engagement with the inner face of the said plate, the opposite face of said disc being lined with a friction material, an inner ring member non-rotatively affixed to said shaft and having a recess in its outer periphery, an outer ring member having a radially extending recess, a ball in said recess adapted to be received in the recess in the inner ring member to constitute a stop, said ball being actuated by a spring disposed in said 45 recess, a spring retaining plate covering said recess and anchored to the outer periphery of said outer ring member, the said plate being formed with an arcuate slot, the said retaining plate having an extension projecting through said arcuate slot, said outer ring member having a roughened surface in engagement with the said friction material, a cover plate carried by said outer ring member and extending over said inner ring member and a spring engaging said 55 cover plate to urge the roughened surface of the outer ring member against the friction material to yieldably maintain the outer ring member in position.

2. Control mechanism for a valve operating 60 shaft comprising a yoke having a front disk formed with an opening through which passes the said shaft, an inner ring member non-rotatably affixed to the said shaft, said inner ring member having an outer cylindrical surface formed with a recess therein, an outer ring member having a bore receiving the inner ring member, and an outer cylindrical surface, said outer ring member being formed with a radially extending recess extending from the outer cylindrical surface to the inner bore, a ball detent disposed in said recess and adapted to be received in the recess in the inner ring member, a spring in the recess of the outer ring member engaging said ball detent to force the same 70 75

against the inner ring member, a retaining plate for said spring anchored to the outer cylindrical surface of said outer ring member and covering said recess in the outer ring member, a cover plate carried by said outer ring member and extending over said inner ring member to main-

tain the latter assembled with the outer ring member, and friction means disposed between the opposite face of the outer ring member and the inner face of the front disk of the yoke.

WALTER S. McDONOUGH.
